Primary Examiner — Marie D. Fast Horse(74) *Attorney, Agent, or Firm* — Fenwick & West LLP(57) **CLAIM**

The ornamental design for a vehicle data acquisition device, as shown and described.

DESCRIPTION

FIG. 1 is a first side view of the vehicle data acquisition device of the present invention.

FIG. 2 is a top view of the vehicle data acquisition device of the present invention.

FIG. 3 is a second side view of the vehicle data acquisition device of the present invention.

FIG. 4 is a bottom view of the vehicle data acquisition device of the present invention.

FIG. 5 is a front view of the vehicle data acquisition device of the present invention.

FIG. 6 is a back view of the vehicle data acquisition device of the present invention; and,

FIG. 7 is a front perspective view of the vehicle data acquisition device of the present invention.

The broken lines in the drawings depict parts of the vehicle data acquisition device that form no part of the claimed design.

1 Claim, 3 Drawing Sheets(56)
